UNITED STATES PATENT OFFICE.

RAY A. NORWOOD, OF COLUMBUS, AND FRANK W. WILSON, OF CORNING, OHIO, AS-SIGNORS OF ONE-HALF TO RAYMOND E. RUSK AND ONE-SIXTH TO J. ED MCKAHAN, BOTH OF COLUMBUS, OHIO, AND ONE-SIXTH TO J. B. LYKINS, OF PORTSMOUTH, OHIO.

REFRIGERATOR.

Application filed February 6, 1924. Serial No. 690,903.

To all whom it may concern:

Be it known that RAY A. NORWOOD and FRANK W. WILSON, citizens of the United States, residing at Columbus, in the county of Franklin and State of Ohio, and Corning, Perry Co., Ohio, respectively, have invented certain new and useful Improvements in Refrigerators, of which the following is a specification.

10 The present invention is directed to improvements in refrigerators and particularly to those of the show case or display type.

The primary object of the invention is to provide a refrigerator of this character so constructed that the refrigerated air will freely circulate within the refrigerator and during the circulation thereof the interior of the refrigerator will be maintained at an even temperature.

15 A further object of the invention is to provide a refrigerator of this character with a refrigerant container having a novel arrangement of cooled air flues therein so arranged that a maximum amount of refrigerating surface will be provided for the air as it circulates through the flues; although the cubic capacity of the container is comparatively small.

With these and other objects in view, as 20 will appear as the description proceeds, the invention consists in the novel features of construction, combinations of elements and arrangements of parts, and hereinafter to be fully described and pointed out in the 25 appended claims.

In the accompanying drawing:

Figure 1 is a front view of the device,

Figure 2 is a vertical sectional view therethrough,

40 Figure 3 is a sectional view on line 3—3 of Figure 2, and

Figure 4 is a sectional view on line 4—4 of Figure 2.

45 Referring to the drawings 1 designates the show case refrigerator which is preferably of such size as to be conveniently placed upon a store counter so as to occupy a minimum amount of space. The case has its bottom 2, sides 3, ends 4 and top 5 of double wall 50 construction, filled respectively with suitable insulating material 6. One side is provided with door openings 7 which are normally closed by hinged mounted doors

8, said doors having a plurality of spaced glass panes 9, this construction being such 55 that articles can be observed in the case, but at the same time assuring that entrance of air will be eliminated as long as the doors are closed. The sides are also provided with similarly arranged panes 10, and if desired 60 the top may also be so constructed.

The top 5 is provided with a centrally located opening 11, there being strips 12 carried by the interior of the top and upon which rests the flanges 12' of the refrigerant container 13, there being a closure 14 for the top opening 11 to permit the container to be conveniently filled with a refrigerant, such as ice and salt. The container depends into the case and divides said 70 case into laterally disposed display compartments 14, said container having its bottom 15 spaced from the bottom of the case to provide a passage 16. Located in this passage is a pan 17 for receiving drip water 75 from the container, the water from said pan being discharged through a suitable drain outlet 18.

Disposed transversely within the container 13 is a plurality of air conducting 80 flues 19, preferably six in number, said flues being disposed in criss-cross relation so that each set of three flues will have their upper or air entrance ends secured in openings 20 formed in the sides 21 of the container, the 85 lower ends being secured in openings 22 formed near the lower ends of said sides whereby the respective ends of said tubes will be in communication with the compartments 14 to permit of circulation of chilled 90 air throughout the entire cabinet to efficiently cool the contents thereof. It will be observed that the respective ends of the flues 19 are curved, as at 23, to eliminate any sharp corners which would tend to restrain 95 the free circulation of the chilled air.

To the exterior surface of the sides 21 of the container are secured in any suitable manner elongated horizontally disposed manifolds 24 which communicate with the 100 upper ends of the flues 19, and extended into said manifolds are the inner ends of the ducts 25, said ducts being supported in any suitable manner by the top 5 of the case 1, said ducts having their outer ends spaced 105 from the ends 4 of the compartments 14 to

permit air to freely enter thereinto for passage through the flues 19. The outer ends of these ducts are provided with a plurality of openings 26 in both sides and bottoms 5 thereof for the passage of air.

The arrangement of the flues 19 in the manner shown not only enhances the circulation of the chilled air, but obviously provides a maximum chilling surface for 10 the air after it passes from the ducts into the adjacent upper ends of the respective flues. This air is then directed downwardly through the flues and a continuous circulation of air is produced, it being of course 15 understood that the air also circulates in the passage 16. The circulation of air is best indicated by the arrows shown in figure 2, and it will be observed that this circulation is such that the cold air will descend in the flues 19 and will consequently 20 be alternately discharged from the lower ends of said flues, thereby thoroughly chilling the interior of the refrigerator.

What is claimed is:

1. A refrigerator of the class described 25 comprising a case, a refrigerant container located in the case and dividing said case into display compartments, flues diagonally arranged in said container, ducts and manifolds in the top of one of said compartments 30 and connected with the upper ends of said flues, with the lower ends of said flues connected with the other compartment.

2. A refrigerator of the class described 35 comprising a case, a refrigerant container depending into the case and dividing the case into independent display chambers, a plurality of flues disposed diagonally within the container, ducts and manifolds in one of said chambers connected with the ends of 40 said flues, the other ends of said flues being connected with the other compartment.

In testimony whereof we affix our signatures.

RAY A. NORWOOD.
FRANK W. WILSON.
